(57) **CLAIM**

The ornamental design for a device for storing papers or the like, as shown and described.

DESCRIPTION

FIG. 1 is a perspective view of a device for storing papers or the like showing our new design;

FIG. 2 is a front view of the device of FIG. 1;

FIG. 3 is a left side view of the device of FIG. 1;

FIG. 4 is a right side view of the device of FIG. 1; and, FIG. 5 is a top view of the device of FIG. 1.

The stippling that can be seen on the flap portion of the claimed design is a type of shading that represents surface material.
